(57) **CLAIM**

The ornamental design for a tray for food products, as shown and described.

DESCRIPTION

FIG. 1 is a perspective view of a tray for food products according to my new design;

FIG. 2 is a left side elevational view of the tray for food products of FIG. 1;

FIG. 3 is a right side elevational view of the tray for food products of FIG. 1;

FIG. 4 is a rear elevational view of the tray for food products of FIG. 1;

FIG. 5 is a front elevational view of the tray for food products of FIG. 1;

FIG. 6 is a top plan view of the tray for food products of FIG. 1;

FIG. 7 is a bottom plan view of the tray for food products of FIG. 1;

FIG. 8 is a perspective view of a second embodiment of a tray for food products according to my new design;

FIG. 9 is a left side elevational view of the tray for food products of FIG. 8;

FIG. 10 is a right side elevational view of the tray for food products of FIG. 8;

FIG. 11 is a rear elevational view of the tray for food products of FIG. 8;

FIG. 12 is a front elevational view of the tray for food products of FIG. 8;

FIG. 13 is a top plan view of the tray for food products of FIG. 8; and,

FIG. 14 is a bottom plan view of the tray for food products of FIG. 8.

The broken lines showing of the lugs in FIGS. 1-14 are for illustrative purposes only and form no part of the claimed design.
